UNITED STATES PATENT OFFICE.

LUTHER D. LOVEKIN, OF PHILADELPHIA, PENNSYLVANIA, ASSIGNOR
OF ONE-HALF TO JOHN PETER MATHIEU, OF PHILADELPHIA, PENN-
SYLVANIA.

EXPANDING AND UPSETTING TOOL.

SPECIFICATION forming part of Letters Patent No. 723,289, dated March 24, 1903.

Application filed March 28, 1902. Serial No. 100,354. (No model.)

To all whom it may concern:

Be it known that I, LUTHER DANIEL LOVEKIN, of the city and county of Philadelphia and State of Pennsylvania, have invented an Improvement in Expanding and Upsetting Tools, of which the following is a specification.

My invention has reference to expanding and upsetting tools; and it consists of certain improvements, which are fully set forth in the following specification and shown in the accompanying drawings, which form a part thereof.

The object of my invention is to provide a simple and efficient tool capable of being easily and expeditiously handled for expanding and upsetting tube ends or other tubular pieces within perforated plates or apertures designed for their reception.

In carrying out my invention I provide a suitable mandrel adapted to be rotated in any convenient manner, the lower end of which is furnished with expanding-rollers, which are preferably made tapered. Within the mandrel I arrange a follower which carries upon its lower end a tapered roller adapted to press upon the expanding-rollers for the purpose of causing them to describe in their travel a circular path of greater or less diameter, as the work may require, and also to reduce their resistance to rotation upon their own axes. The tapered follower-roller and its follower-shaft are moved longitudinally through the mandrel by hand-operated means, which may be manipulated while the expanding operation is being carried on by the expanding-rollers. Combined with the expanding devices above mentioned I provide the mandrel with upsetting-rollers, arranged about its body and at a distance from the expanding-rollers. The rollers are grooved, so as to upset and bead the edge of the tube to make a tight and finished joint—such, for example, as suitable for securing boiler-tubes within the head of the shell.

My invention further includes details of construction, which, together with the features above mentioned, will be better understood by reference to the drawings, in which—

Figure 1 is a sectional elevation of my im-

proved expanding and upsetting tool. Fig. 50
2 is an end view of the same. Fig. 3 is a sectional elevation showing a modification of the antifriction devices for the follower-roller. Fig. 4 is a sectional elevation of a modified form of the lower portion of my tool. 55 Fig. 5 is an elevation of the same. Fig. 6 is an end view of the same. Fig. 7 is a cross-section on line 7 7 of Fig. 4. Fig. 8 is a sectional elevation of the tube before being expanded and upset, and Fig. 9 is the tube after 60 being expanded and upset.

2 is a mandrel which is substantially cylindrical in shape, having at the bottom a tubular part and at the top a shank by which it may be held and rotated. In the lower 65 end of the tubular part of the mandrel I arrange the expanding-rollers 3, preferably three in number, which are set into sockets 5, formed with curved walls, which hold the rollers from falling out of the mandrel. These 70 expanding-rollers 3 are retained upon the mandrel by an annular plate 6, held to the bottom of the mandrel by screws 4. The surfaces of these rollers are exposed upon the outside of the mandrel, so as to operate upon 75 the work to be expanded, and are also exposed upon the inside of the mandrel, so as to be operated upon by the follower-roller 10, located within the chamber 7 of the tubular part of the mandrel. This follower-roller 10 80 is tapered, with the smaller end downward, and acts upon the expanding-rollers 3 to press them apart, so that they are made to describe circles of gradually-increasing diameters in the expanding operation when desired. The 85 rollers 3 are also preferably tapered, but in the reverse direction to the roller 10. When the inner diameter of the work to be expanded is uniform, the tapers of the rollers 3 and 10 are the same; but it would be different where 90 the inner surface of the tubes or bushing or ring to be expanded is not of uniform diameter, as will be readily understood.

The follower-roller 10 is loosely sleeved upon a spindle 9 of a follower-shaft 8 and 95 held thereon by a nut 12. When the roller 10 is retracted, it is inclosed within the chamber 7, and is thus protected when out of use.

The follower-roller is operated by the following devices: The middle portion of the mandrel is slotted, as at 13, and the upper portion of its body above the slot is screw-threaded 5 at 14 and provided with a nut 17. A controller-ring 15, provided with suitable handles or parts for the operator to grasp, is loosely sleeved over the mandrel-body and journaled in bearings 18 on the mandrel and 10 on the nut 17. In this manner the controller-ring may be freely rotated for purposes to be set out later on. The mandrel-body is bored through almost to the shank and is filled with the vertically-adjustable 15 follower-shaft 8, having at its upper end a transverse key 20, which is guided in the slots 13 of the mandrel, so as to be prevented from turning, the ends of said key projecting beyond the mandrel-body and connecting with 20 the controller-ring by screw-threads upon its outer ends engaging internal threads 19 on the interior face of the controller-ring. It will now be seen that by turning the controller-ring or holding it while the mandrel 25 is rotated the follower-shaft will be caused to move longitudinally through the mandrel, and thereby impart a longitudinal movement to the follower-roller 10, located on the spindle of the said follower-shaft. Any other 30 suitable means may be employed for imparting a longitudinal movement to the follower-roller; but that shown I have found most excellently adapted to the purpose and equally effective whether the mandrel is rotated or 35 the work rotated or both rotated. While I have shown the controller-ring as provided with handles to turn it, an ordinary hand-wheel may be used instead, if preferred.

As the roller 10 is subjected to heavy strains 40 in an upward direction when spreading the rollers 3 in expanding the tube or other work, I find it most advantageous to provide means to take this thrust with the least possible liability of wear from friction. To accomplish 45 this, I provide the follower-shaft with several antifriction rings or collars 11, resting upon one another and between the end of the roller 10 and the shoulder upon the lower end of said shaft, said rings or collars encircling 50 the spindle 9. These rings or collars take up the end thrust of the roller and permit it to revolve freely under the action of the rotating expanding-rollers 3. While the roller 10 is carried upon the spindle 9, it need not fit 55 the same tightly, as it is centered by the three expanding-rollers 3, and is therefore preferably made with some small provision for lateral play upon its spindle, as shown.

At a distance above the expanding-rollers 60 3 I arrange three or more upsetting and beading rollers 21, the same being carried upon radial axes 22, one end of which is set into the body of the mandrel and the other or outer end supported by brackets 23, secured to the 65 mandrel by screws or other convenient means. As shown, the mandrel-body is somewhat recessed, as at 32, into which to let the side of

the upsetting-rollers 21, so that the annular grooves of said rollers shall come in alignment with the edge of the tube being upset. 70

It will now be understood that if the mandrel be inserted within a tube 28, Fig. 8, and revolved while depressing the follower and follower-roller 10 the tube will be expanded within the circular hole or aperture in the 75 plate or head 31, as shown at 29 in Fig. 9. When this is done, the follower-roller 10 is retracted and the mandrel inserted farther into the tube until the upsetting-rollers 21 press upon the end of the tube. The action of the rollers 21 80 then upsets and beads the end of the tube, as shown at 30 in Fig. 9, thereby firmly securing the tube in the head 31 and making a steam-tight joint. The use of this tool is especially advantageous in securing boiler- 85 tubes in the heads of boilers.

The tool may be modified in the following particulars, if so desired: In place of the anti-friction rings or collars 11 between the roller 10 and the shoulder of the follower 8 I may 90 employ antifriction-rollers or ball-bearings, as shown at 24 in Fig. 3. The rollers 3 may be held in the mandrel in the manner shown in Figs. 4, 5, and 6—namely, by having trunnions which fit into bearing-slots in the mandrel. In this case the rollers 3 are put into position from the inside of the mandrel, and while prevented from falling outward, because of the trunnions and bearings in the mandrel, they cannot fall inward, because of 95 the roller 10. These figures also show a modified manner of carrying the upsetting and beading rollers 21. In this case the roller-carrying brackets 23 are integral with 100 a collar 26, fitting the mandrel and held by 105 a shoulder against longitudinal movement and also keyed to the mandrel at 27 to prevent turning thereon. The mandrel may have longitudinal slots or grooves 25 to permit the passage of the inner end of the journals 22 of the upsetting-rollers, so that these 110 rollers may be attached to the collar 26 before the same is slipped up into place and carry with it the rollers 21. It will therefore be understood that I do not limit myself 115 to any particular manner of attaching the rollers 21 or of supporting the rollers 3, and hence the details of construction may be varied without departing from the spirit of my 120 invention.

Matters shown in this application and not claimed constitute subject-matter of other pending applications of mine, more particularly Serial No. 100,351, of 1902, Serial No. 100,353, of 1902, and Serial No. 100,355, of 125 1902.

Having now described my invention, what I claim as new, and desire to secure by Letters Patent, is—

1. In a tool for expanding and upsetting 130 pipe, the combination of a mandrel having a tubular end, a series of expanding-rollers carried by the tubular end of the mandrel and movable to and from each other, a cen-

tral roller within the tubular mandrel and against which the expanding-rollers rest and upon which they revolve when doing their work of expanding the tube, a central support for the central roller for supporting it within the mandrel but out of contact with its interior walls, and one or more grooved upsetting-rollers journaled upon horizontal axes radiating from the mandrel at a considerable distance from its end so as to be out of transverse alinement with the expanding-rollers but maintaining relatively fixed relation to said rollers.

2. In a tool for expanding and upsetting pipe, the combination of a mandrel having a tubular end and a shoulder at a distance from the end, a series of expanding-rollers carried by the tubular end of the mandrel and movable to and from each other, a central roller within the tubular mandrel and against which the expanding-rollers rest and upon which they revolve when doing their work of expanding the tube, a central support for the central roller for supporting it within the mandrel but out of contact with its interior walls, one or more grooved upsetting-rollers journaled upon horizontal axes radiating from the mandrel at considerable distance from its end so as to be out of transverse alinement with the expanding-rollers, and a ring fitting about the mandrel adjacent to the shoulder and provided with brackets supporting the outer ends of said upsetting-rollers.

3. In a tool for expanding tubes, the combination of a mandrel adapted to be held when using the tool, expanding-rollers carried by the mandrel and adapted to project beyond the outer surface thereof, a longitudi-

nally-adjustable follower carried by the mandrel having an annular shoulder, a tapered 40 roller journaled upon the follower and moved thereby and adapted to receive the thrust of the expanding-rollers when in the act of expanding the tube, antifriction-bearings between the end of the follower-roller and the 45 shoulder of the follower, means to move the follower longitudinally through the mandrel without rotating it, grooved upsetting-rollers rotating in vertical planes and upon axes 50 radially arranged to the mandrel, and supporting means for the upsetting-rollers extending upward or away from the expanding-rollers and secured to the mandrel.

4. In an expanding-tool, the combination of the mandrel having a tubular end portion 55 provided with sockets 5 opening outward at the rim, tapered expanding-rollers 3 carried in said sockets and of larger diameter than the outer openings of the sockets, an annular ring 6 secured to the end of the mandrel to 60 close the bottom of the sockets and to hold the rollers in place, a tapered follower-roller 10 arranged within the mandrel and adapted to spread the expanding-rollers 3, means for moving the follower-roller longitudinally 65 without rotating it, grooved upsetting-rollers 21 rotating in vertical planes, and downwardly-extending brackets supporting the outer ends of said rollers and secured to the mandrel above them.

In testimony of which invention I have hereunto set my hand.

L. D. LOVEKIN.
